CLAIM

The ornamental design for a a stethoscope head, as shown and described.

DESCRIPTION

FIG. 1 is a rear perspective view of an embodiment for a new and ornamental design for a stethoscope head;

FIG. 2 is an upper perspective view thereof;

FIG. 3 is a front elevation view thereof;

FIG. 4 is a rear elevation view thereof;

FIG. 5 is a left side elevation view thereof, the right side elevation being a mirror image;

FIG. 6 is a top plan view thereof; and,

FIG. 7 is a bottom plan view thereof.

The portions in the drawings shown in phantom are for environment only and form no part of the claimed invention.

1 Claim, 7 Drawing Sheets(56)
